APPARATUS FOR TREATING YARN

Homer V. Lang, Charlotte, N. C.

Application May 3, 1937, Serial No. 140,477

8 Claims. (Cl. 68—205)

This invention relates to a machine for conditioning textile fibres such as packages of yarn in the form of bobbins, cops and the like. In the textile art, thread on the bobbin is treated with a solution, with certain ingredients therein, in order to set the twist in the thread before it is used for other purposes. In machines heretofore used for moistening or conditioning yarn it has been necessary to employ machinery which occupied considerable floor space so that all portions of the packages would be subjected to this treating solution. Other machines have been provided which did not occupy a great deal of floor space but yet the means for turning the packages while being subjected to the treating solution entailed mechanism which has not proven to be efficient and practical.

It is therefore, an object of this invention to provide an apparatus which has means for turning the packages while the same are being subjected to a spray of the treating solution so that all portions thereof may be equally treated. This turning means comprises a pair of beveled baffles or guards which are oppositely disposed above a conveyor belt and in the path of travel of the packages. As the conveyor passes beneath these guards or baffles the packages contact these guards and are caused to creep laterally of the conveyor simultaneously as the treating solution is being sprayed thereon. It is evident that this lateral creeping motion of the packages, first from one side of the conveyor and then to the other, will cause the bobbins thereon to be rotated so as to expose all portions of their surfaces to the downwardly projected treating solution.

It is a further object of this invention to provide an apparatus of a class described which has a conveyor belt formed substantially of flat slats with the upper surfaces thereof occupying the same plane. The edges of each of the slats have a slight rim portion integral therewith which forms a dished portion in the central portion thereof for holding some of the treating solution so that the lower side of the package as it is turned thereon will absorb the solution in this dished portion. At the same time the upper portion of the package is absorbing the downwardly directed spray. In other words, the lower side of the package is absorbing the liquid which is sprayed onto the slats while the upper portion of the package is absorbing the spray which is directed downwardly from the nozzles. The packages are turned by the side guards, which creep the packages from one side of the conveyor to the other.

It is a further object of this invention to provide an apparatus for treating yarn comprising a conveyor upon which the bobbins are placed for treatment with means for rotating the conveyor beneath a plurality of thin sheet sprays which are directed downwardly upon the packages from spaced nozzles. These nozzles are of a peculiar design which spray the liquid therefrom in a sheet formation so that at the point where the liquid strikes the top of the conveyor the longest side of the sheet will be disposed at right angles to the path of travel of the conveyor. By providing this nozzle it is evident that all of the packages which are disposed on the conveyor will be treated with an equal amount of solution. In the conventional nozzles the cross sectional area of the spray at the point of contact with the conveyor is circular in shape; consequently, when the packages pass beneath this spray those packages which traverse the central portion of this circular spray will be subjected to more liquid than those which traverse the outer edge portions of the spray. I have arranged a plurality of my improved nozzles in alignment directly above the conveyor belt so that as many of the same may be used as desired to vary the quantity of solution which is sprayed upon the packages as they pass beneath the spray nozzles.

Some of the objects of the invention having been stated, other objects will appear in the description hereinafter following, when taken in connection with the accompanying drawings, in which:

Figure 1 is an elevation of the invention showing portions of the liquid container broken away; 35

Figure 2 is an elevation looking at the opposite side of Figure 1;

Figure 3 is a plan view of the invention;

Figure 4 is an elevation looking at the left-hand end of Figures 1 and 3; 40

Figure 5 is a longitudinal, sectional view taken along the line 5—5 in Figure 3;

Figure 6 is an enlarged sectional view, showing certain portions thereof in elevation and taken through a portion of the spray head shown in 45 Figure 5;

Figure 7 is an enlarged sectional plan view taken along the line 7—7 in Figure 6 showing a detail of my improved nozzle;

Figure 8 is a sectional view through the bypass check valve shown in the lower left-hand portion of Figure 5 which works in connection with the pump mechanism; 50

Figure 9 is an inverted isometric view of a portion of a slightly modified form of conveyor belt; 55

Figure 10 is an isometric view showing the top portion of one of the slats used in Figure 9.

Referring more specifically to the drawings, the numeral 10 denotes the back end frame support 5 which has resting on the upper portion thereof horizontally disposed angle members 11 and 12, the front end of said angle members being secured to the upper portion of inclined angle supports 13 and 14 respectively. Secured to the inclined 10 members 13 and 14 and near the lowermost portion thereof are angle struts 15 which project rearwardly of the machine and are secured to the lowermost portion of support 10. Also secured to the lowermost portion of inclined members 15 16 are shoes 16, said shoes having solts 18 therein into which bearings 19 are adapted to slide. These bearings house the ends of shaft 20 upon which sprockets 21 are fixedly secured. The positions of bearings 19 are adjusted by 20 means of set screws 22 which are threadably secured in outstanding lugs 22a in the upper end of brackets 16 with the lower ends of said screws contacting the upper side of the bearings 19.

Suitable sprocket chains 24 are adapted to be 25 mounted upon the sprockets 21 and 28, and upon these sprocket chains cross bars 25 and 25a are secured for supporting bobbins 26 and conveying them to the position where they are to be treated. The conveyor is broadly indicated by reference 30 character 27. The cross pieces 25a are higher than the pieces 25 so that a predetermined amount of packages will be collected and conveyed upwardly. The sprockets 28 are fixedly secured on cross shaft 29, said shaft having its 35 ends rotatably mounted in the inclined members 13 and 14. These inclined members 13 and 14 are spaced apart from each other by means of struts 30.

In order to provide means for holding a supply 40 of bobbins or packages 26, a suitable hopper 31 has been mounted upon the top of inclined members 13 and 14 with its sides surrounding the top side of the conveyor. When the bobbins are placed in the hopper 31 as shown in Figure 45 5, the high cross pieces 25a will collect a portion thereof and convey them towards the top of the conveyor where they will be delivered to a horizontally disposed conveyor 33.

This conveyor comprises a plurality of horizontally disposed rods 34 which are secured between 50 sprocket chains 35. These chains, in turn, are rotatably mounted upon sprockets 37 and 38 which are fixedly secured upon shafts 39 and 40 respectively. The ends of the shafts 39 and 40 are rotatably mounted in suitable bearings secured to the horizontal angle members 11 and 12.

The sides of the conveyor 33 are enclosed by side walls 45 and 46 mounted upon the angle members 11 and 12 respectively. These sides 60 have beveled baffles 47 and 48 secured thereto with the lower end of the baffles extending over the top of the conveyor belt 33. When the inclined conveyor 27 delivers the packages to the horizontal conveyor 33 as shown in Figure 3, the 65 movement of conveyor 33 will cause the bobbins to first contact the baffle 48. Upon further movement of the conveyor the bobbins will be caused to creep and roll towards the observer in Figure 3 at the same time the spray will be projected downwardly thereon from the nozzles. The baffle 70 47, which is secured on the opposed side of the conveyor, will then be contacted by the bobbins on this side of the conveyor thereby causing the whole batch to creep and roll away from the observer in Figure 3. It will be noted that the

baffles 47 and 48 are placed in a staggered relation to each other so that all of the bobbins will be allowed to creep and roll transversely of the conveyor until the center line of the spray head has been reached and then the other baffle 47 will move these same bobbins transversely in the opposite direction until they have passed out from beneath the spray. This creeping or shuffling of the bobbins causes all portions thereof to be turned and exposed to the spray.

The conveyor belt 33 is held in taut position by means of the bearings 50 which are secured to the outside of angle members 11 and 12. The ends of the shaft 40 are rotatably mounted in blocks 51 which blocks are slidably mounted in 15 slots 50a in these bearings. Set screws 52 normally contact these blocks to hold the shaft 40 in the desired position so that the belt will remain taut.

In order to provide means for driving the conveyor belts 27 and 33, a suitable motor 55 has been mounted upon bracket 56 which extends out from the framework of the apparatus. This motor has a motor shaft 57 and a pulley 58 upon which a belt 59 is mounted. This belt is also mounted upon a larger pulley 60 which is secured to the end of a shaft 61. The shaft 61 is rotatably mounted in inclined angle members 13 and 14 and has secured on the other end thereof a pinion 62 which meshes with a larger gear 63, 30 said gear 63 being fixedly secured on shaft 29. Upon rotation of the motor shaft 57, counter-clockwise motion is imparted to the shaft 29 through the members just described, to cause the conveyor belt 27 to deliver predetermined quantities of bobbins 26 to the conveyor 33.

The shaft 29 also has a sprocket 64 secured thereon upon which is mounted a sprocket chain 65. This chain is also mounted upon a second sprocket 66 which is fixedly mounted upon the shaft 39. The counter-clockwise motion of shaft 29 will therefore be imparted to the shaft 39 which in turn will cause the conveyor belt 33 to transport the bobbins toward the rear of the machine.

Secured between the upper sidewall portions 46 and 45 is a pair of rods 70 upon which is secured a bracket 71 which supports a T-shaped pipe fitting 72, into which liquid is delivered from hose 73. Leading from opposed ends of member 72 are suitable short pipes 75 which have the other ends thereof connected to through valves 76. (Figures 5 and 6.) Nozzles 77 are connected to the lower portion of the valves 76 and these nozzles have an orifice 78 in the lower portion thereof through which the spray is forced. (Figure 7.) It will be noted that the lower portion of the nozzles have an elongated groove 79 which is diametrically disposed relative to the orifice 78. Also, on the inside of the nozzle are diametrically disposed grooves 80 which intersect the upper portion of the orifice. The liquid moves downwardly through the orifice 78 and due to the grooves 79 and 80 the spray is caused to assume substantially a rectangular shape at the conveyor thereby maintaining an even width of spray across the conveyor. This will insure that all portions of the conveyor as it passes beneath this spray will be subjected to an equal amount of treating solution. As heretofore stated, if the spray were circular in shape at the point where it contacted the conveyor then the portions of the conveyor which pass beneath the central portion of this circular area will be subjected to 75

more treating solution than those portions which pass through the outer edges thereof.

Each of the valves 76 has leading therefrom another pipe 85 which is connected to a spray head 86, said head being identical in all respects to the spray head 77 recently described. All of the spray heads such as 77 and 86 are placed in alignment with each other substantially over the center line of the conveyor so that variable quantities of liquid may be delivered to the bobbins on the conveyor. If desired, by means of the wheels 87 of the valves 76 the ports 88 which lead to the nozzles 77 may be closed and only the outer spray heads 86 used.

15 The T-fitting 72 has a gauge 90 secured thereto which registers the amount of pressure set up in spray heads and the delivery hose 73. This delivery hose has its lower end connected to the outlet pipe 91 of pump 92, said pump being driven by the motor shaft 57 simultaneously with the driving of the conveyors. The pump has an inlet pipe 93 leading thereto, to which is secured a hose 94. This hose leads to the lower portion of container 95 in which the treating solution is placed. When the motor is in operation the pump draws the solution from the container 95 through the pump 92, hose 73, and forces it out through the spray heads 77 and 86 onto the bobbins 26 which are disposed upon the conveyor 33.

30 If for any reason, it is desired to use only the outer spray heads 86 then the ports 88 are closed.

Due to the closing of the ports 88, but at the same time maintaining the same speed of the motor and pumps, a pressure will naturally be built up in the hose 73. In order to neutralize this excess pressure and prevent more solution from passing through the nozzles which are then in use, a suitable by-pass pipe 97 has been provided which has one end thereof connected to the outlet pipe 91 and its other end connected to the inlet pipe 93. Disposed in this by-pass is a spring check valve 98 which has a ball 99 therein normally closing a port 100. A spring 101 normally presses the ball to a closed position, (Figure 8), but due to the adjustment of the pressure on spring 101 liquid will be allowed to flow through the port 100 and into the intake side of the pipe line when an excessive pressure is built up in the hose 73.

50 The point at which liquid will be caused to flow through the port 100, is varied by means of cap 98a which is threadably secured on the end of the check valve casing 98 to vary the amount of pressure exerted upon the spring 101 and ball 99.

55 The excess liquid which is sprayed upon the bobbins and the conveyor is caught by a suitable inclined pan 103 which is disposed directly beneath the conveyor belt 33. This pan has an outlet 104 in the side portion thereof at a point 60 where the excess liquid will be delivered to the opening 105 in the top of container 95. This opening has a strainer 106 disposed therein for removing any objectionable matter from the liquid. Figures 9 and 10 show a slightly modified 65 form of conveyor belt which may be used to replace conveyor 33. This conveyor comprises a plurality of slats 108 which have raised ribs 108a on the top surface thereof thereby forming a dished channel 108b for holding a limited supply 70 of the treating fluid from the nozzles. The packages of yarn which rest upon these slats will absorb the treating fluid in these channels. These slats are secured to suitable links 109 of a sprocket chain in the manner shown in Figure 9.

75 In the drawings and specification there has

been set forth a preferred embodiment of the invention, and although specific terms are employed, they are used in a generic and descriptive sense only, and not for purposes of limitation, the scope of the invention being set forth in the 5 appended claims.

I claim:

1. Apparatus for applying a treating solution to packages of yarn comprising a horizontally disposed conveyor, a spraying nozzle disposed above the conveyor for directing a treating fluid onto the conveyor and the packages thereon, a horizontally inclined baffle disposed above the conveyor and in close proximity thereto and laterally of the spraying nozzle to move the packages laterally of the conveyor when the conveyor moves the packages in contact with the baffle, as they are passing beneath the spraying nozzle. 15

2. Apparatus for applying a treating solution to packages of yarn comprising a horizontally 20 disposed conveyor, a spraying nozzle disposed above the conveyor for directing a treating fluid onto the conveyor and the packages thereon, a horizontally inclined baffle disposed above the conveyor and in close proximity thereto to move 25 the packages laterally of the conveyor and laterally of the spray from the spraying nozzle when the conveyor moves the packages in contact with the baffle, and an upwardly inclined trough disposed at one end of said conveyor and having a 30 second conveyor for depositing packages of yarn onto the first conveyor.

3. Apparatus for applying a treating solution to packages of yarn comprising a horizontally disposed endless conveyor, a plurality of nozzles 35 disposed above the conveyor in a vertical plane longitudinally bisecting the conveyor, and constructed to project fan-shaped sprays transversely of the line of travel of the conveyor, an angularly disposed baffle disposed on one side 40 of the conveyor for moving and rolling the packages laterally of the conveyor and longitudinally of the fan-shaped sprays as the conveyor pushes the packages against the baffle and a second baffle disposed on the other side of the conveyor for 45 pushing the packages in the opposite direction on the conveyor when the conveyor pushes the packages against said baffle.

4. Apparatus for applying a treating solution to packages of yarn comprising a horizontally 50 disposed endless conveyor, sidewalls disposed on each side of the conveyor, a plurality of nozzles disposed above the conveyor for projecting fan-shaped sprays of treating solution onto the packages on the conveyor, an inclined trough having 55 its upper end disposed near the intake end of the conveyor, a second conveyor disposed in said inclined trough, said second conveyor having intermittently disposed projections for engaging packages piled in the trough and delivering a predetermined quantity of the packages to the first conveyor and a baffle secured to one of the side walls associated with the first conveyor adjacent said nozzles and projecting in an inclined angle over a portion of the first conveyor to move the 60 packages laterally of the conveyor and longitudinally of said sprays as the conveyor moves the packages relative to said sidewalls.

5. Apparatus for applying a treating solution to packages of yarn comprising a horizontally 70 disposed endless conveyor, sidewalls disposed on each side of the conveyor, a plurality of nozzles disposed above the conveyor for projecting sheet-like sprays of treating solution onto the packages on the conveyor, an inclined trough having its upper 75

end disposed near the intake end of the conveyor, a second conveyor disposed in said inclined trough, said second conveyor having intermittently disposed projections for engaging packages piled in the trough and delivering a predetermined quantity of the packages to the first conveyor, a baffle secured to one of the side walls associated with the first conveyor and projecting in an inclined angle over a portion of the first conveyor to move the packages laterally of the conveyor and longitudinally of the sheet-like sprays as the conveyor moves the packages relative to said sidewalls, and a second baffle secured to the other sidewall for moving the packages laterally of the conveyor after they have passed the first baffle in a direction opposed to the movement imparted to the packages by the first baffle.

6. Apparatus for applying a treating solution to packages of yarn comprising a horizontally disposed endless conveyor, side walls disposed on each side of the conveyor, a plurality of nozzles disposed above the conveyor for projecting sprays of treating solution onto the packages on the conveyor, an inclined trough having its upper end disposed near the intake end of the conveyor, a second conveyor disposed in said inclined trough, said second conveyor having intermittently disposed projections for engaging packages piled in the trough and delivering a predetermined quantity of the packages to the first conveyor, a baffle secured to one of the side walls associated with the first conveyor and projecting in an inclined angle over a portion of the first conveyor to move the packages laterally of the conveyor while the packages are subjected to said sprays and as the conveyor moves the packages relative to said sidewalls, the first conveyor having a plurality of transversely disposed slats for supporting the packages, and each slat having a concave upper side for retaining some of the sprayed treating solution to be absorbed by the yarn on the packages which are resting in alignment with the slats.

7. Apparatus for applying a treating solution

to packages of yarn comprising a horizontally disposed endless conveyor, sidewalls disposed on each side of the conveyor, a plurality of nozzles disposed above the conveyor for projecting transversely disposed sheets of spray of treating solution onto the packages on the conveyor, a baffle secured to one of the sidewalls associated with the conveyor and projecting in an inclined angle over a portion of the conveyor to move the packages laterally of the conveyor and longitudinally of the sheets of spray as the conveyor moves the packages relative to said sidewalls, the conveyor having a plurality of transversely disposed slats for supporting the packages, and each slat having a concave upper side for retaining some of the sprayed treating solution to be absorbed by the yarn on the packages which are resting in alignment with the slats.

8. Apparatus for applying a treating solution to packages of yarn comprising a horizontally disposed endless conveyor, sidewalls disposed on each side of the conveyor, a plurality of nozzles disposed above the conveyor for projecting a plurality of sheet-like sprays of treating solution onto the packages on the conveyor, the sheets of spray extending laterally of the conveyor, a baffle secured to one of the side walls associated with first conveyor and projecting in an inclined angle over a portion of the conveyor to move the packages laterally of the conveyor as the conveyor moves the packages relative to said sidewalls, and a second baffle secured to the other sidewall for moving the packages laterally of the conveyor after they have passed the first baffle in a direction opposed to the movement imparted to the packages by the first baffle, the conveyor having a plurality of transversely disposed slats for supporting the packages, and each slat having a concave upper side for retaining some of the sprayed treating solution to be absorbed by the yarn on the packages which are resting in alignment with the slats.

HOMER V. LANG.
